CLAIM

The ornamental design for a/an microwave splatter cover, as shown and described.

DESCRIPTION

FIG. 1 is a front perspective view of a microwave splatter cover, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a perspective view of the microwave splatter cover in a flattened state of use;
FIG. 10 is an enlarged detail view of area 10 in FIG. 1; and,
FIG. 11 is an enlarged detail view of area 11 in FIG. 5.
The short dash broken lines in FIGS. 2 and 4 illustrate portions of the microwave splatter cover that form no part of the claimed design. The long dash broken lines encircling portions of the microwave splatter cover in FIGS. 1 and 5 show the boundaries of the enlarged views in FIGS. 10 and 11 and form no part of the claimed design.

1 Claim, 11 Drawing Sheets
